WINDING MACHINE

Ernest R. Swanson, Cranston, R. I., assignor to
 Universal Winding Company, Boston, Mass., a
 corporation of Massachusetts

Application August 22, 1934, Serial No. 741,012

21 Claims. (Cl. 74—217)

This invention relates to winding machines for winding cops, cones, cheeses and other forms of packages of thread, yarn, cord and similar strand materials, hereinafter referred to generally by 5 the term "yarn"; and particularly to winding machines wherein the package is rotated by contact with a drive-roll or drum. Specifically, the invention consists in a ribbon-breaker, so-called, which operates to control the disposition of the 10 turns of winding on the surface of the package to prevent the formation of bands or "ribbons" in which the yarn coils are crowded together or "piled".

One object of the invention is to provide a 15 simplified mechanism incorporated in the driving means of the winding machine and operating to disrupt the synchrony between the rotation of the package and the traverse of the yarn during the winding.

Another object of the invention is to provide a 20 mechanism of the type indicated for periodically varying the speed ratio between the rotation of the package and the traverse of the yarn-guiding means at recurring cycles throughout the winding.

Another object of the invention is to provide a 25 mechanism of the type indicated adapted for use on machines embodying a single rotating element for driving the package and traversing the yarn; for example, a drive-roll with a helical yarn-guiding groove or grooves on its periphery, the 30 ribbon-breaking means operating to effect rapid fluctuations in the speed of the roll to cause slippage between the roll and the package.

Another object of the invention is to provide a 35 mechanism of the type indicated which is completely automatic in its operation and adjustable to meet all requirements.

Further objects of the invention are set forth in the following specification which describes a 40 preferred form of construction of the device, by way of example, as illustrated by the accompanying drawings.

In the drawings:

Fig. 1 is a front elevation of a portion of a winding frame or gang winder showing the essential elements of the winding mechanism of one unit thereof in connection with the driving means which embodies the present improved ribbon-breaker or speed-changing device;

Fig. 2 is an end view of the winding frame showing the driving mechanism thereof connected to be driven by an electric motor;

Fig. 3 is an enlarged end view of the present 55 improved ribbon-breaking mechanism;

Fig. 4 is a detailed sectional view of the same taken on line 4—4 of Fig. 3;

Fig. 5 is a transverse sectional view through the mechanism taken on line 5—5 of Fig. 4; and

Fig. 6 is a detailed end view of the mechanism 5 for oscillating the stop-motion rocker-shaft from the ribbon-breaker rocker-shaft.

The present invention relates particularly to means for imparting an alternately accelerated and retarded rate of speed to one of the winding elements of the machine, for example, the drive-roll for rotating the package; or in other instances it may be applied to the drive for the 10 yarn-traversing means when the latter is operated independently of the drive-roll. More specifically, the invention contemplates the employment of automatically-operated means for periodically tightening and loosening the belt which 15 transmits motion to the driven element whereby an acceleration and deceleration in the speed of 20 said element is effected.

Referring to the drawings, the winding machine herein illustrated by way of example is of the double gang type comprising a plurality of winding units arranged in series along the opposite sides of a horizontal frame or bed 2 which is supported at its ends by suitable legs 3. Spaced along the top of the bed 2 are a series of brackets 4 which support bearings for the driving-shafts 25 and other parts of the several winding mechanisms, two opposite units being located between each pair of brackets but only one unit being 30 herein shown.

In the construction of the machine as shown in Fig. 1 the winding mechanism comprises only 35 two principal elements, namely, the winding-mandrel or spindle 15 on which the yarn-receiver or cop-tube C is rotatably supported, and the drive-roll 10 for rotating the yarn-receiver and in which is embodied the means for traversing 40 the yarn back and forth axially of the package being wound. In this form of construction the usual reciprocating thread-guide is dispensed with, the drive-roll having its peripheral surface provided with a helical groove or grooves 8 and 9 45 extending in opposite directions and adapted to receive the strand of yarn to guide it back and forth between the ends of the package. This particular form of traversing-means is shown and described in United States Letters Patent No. 50 1,749,355 dated March 4, 1930. It is to be understood, however, that the present ribbon-breaker or speed-changing device is adapted for use on 55 winding machines of other types, for example, those wherein the package is driven by contact 55

with a drive-roll and the yarn traversed by means of a reciprocating guide, or with any other arrangement of drum-driven winders.

In the form of construction shown in Fig. 1 5 the drive-rolls 10 are carried on and rotated by a horizontal shaft 11 journaled in ball-bearings 12 on the brackets 4; the shaft 11 being extended throughout the whole length of the gang machine to carry the drive-rolls for any desired number 10 of winding units. A second, parallel shaft 13, also journaled in bearings on the bracket 4, carries the drive-rolls, not herein shown, for the other series of winding units arranged on the opposite side of the winding frame or at the right-hand 15 side as viewed in Fig. 2.

The present machine is shown as adapted for winding packages of conical form with the yarn built up on a suitable axial core or receiver, a wooden or fiber conical cop-tube C being illustrated in Fig. 1 as mounted to rotate on the winding-spindle or mandrel 15. The winding-spindle 15 is swiveled to the forward end of a weighted arm 16 which is pivotally supported at its rearward end to adapt the surface of the yarn-receiver C, or of the package P, to be held firmly in contact with the periphery of the drive-roll 10. As the yarn is built up on the cop-tube C it forces the latter upwardly with the arm 16 swinging on its pivot in the manner common to machines of 30 the present type.

Each winding unit is equipped with a suitable stopping mechanism, indicated generally by the reference numeral 17 in Fig. 1, which is automatically actuated when the yarn breaks or its supply is exhausted to arrest the winding operation by raising the package away from the drive-roll 10. The operation of the stopping mechanism is initiated by a rocker-shaft 19 journaled in bearings in the frames 4 and extending 40 throughout the entire length of the machine. The rocker-shaft 19 is constantly oscillated during the operation of the machine by means to be later described.

The combined driving and ribbon-breaking 45 mechanism of the machine is constructed and arranged as next described. Bolted to the top of the bed 2 are a pair of spaced brackets or cross-frames 20 and 21. The drive-roll shaft 11 projects beyond the bearing 12 in the end bracket 4 50 with its reduced extremity 22 journaled in a ball-bearing 25 on the frame 20, see Fig. 4. A belt-pulley 30 is keyed to the reduced end 22 of the shaft 11 at 28 and secured in place by means of a nut 29. The periphery of the pulley 30 is 55 provided with spaced V-shaped grooves 27 for a pair of belts 99 by which it is driven from means to be later described.

The opposite drive-roll shaft 13 is somewhat longer than the shaft 11, above mentioned, with 60 its reduced end projecting through a clearance opening in the frame-member 20 and journaled in a ball-bearing on the frame-member 21. Mounted fast on the reduced end of the shaft 13 is a pulley 35 of the same form and size as the pulley 30 previously described. The pulley 35 is keyed to the shaft 13 at 28 and held axially in place by a nut 29, see Fig. 3.

Arranged for vertical adjustment on the facing 70 sides of the frame-members 20 and 21 are two complementary brackets 37 and 38, see Fig. 4. The brackets 37 and 38 are received in vertical grooves or guideways 39 on the frames 20 and 21 and held in adjusted position by means of disks 40 eccentrically mounted on the reduced portions 75 41 of a shaft 42. The ends 41 of the shaft 42

project through holes in the frames 20 and 21 with nuts 43 screwed onto their threaded extremities and set up against the side of the frames to hold the shaft from turning. The peripheries of the eccentric disks 40 engage the opposite 5 sides of horizontal slots 45 on the outer sides of the brackets 37 and 38, see Fig. 5, with the main portion of the shaft 42 passing through vertical openings 46 in the webs at the side of the slots.

The brackets 37 and 38 support a rockable housing 50 enclosing mechanism to be later described and carrying pulleys, to be later described, belted to the pulleys 30 and 31. The brackets 37 and 38 are vertically adjustable for regulating the tension of the belts connecting the pulleys 30 and 35 15 with the driving pulleys carried by the housing 50. To adjust the brackets 37 and 38 the nuts 43 are loosened, after which the shaft 42 may be manually turned in either direction by inserting a rod through a hole 49 in the shaft to serve as a 20 lever. As the shaft 42 is turned the eccentric disks 40 act on the sides of the grooves 45 to raise or lower the brackets 37 and 38 in the guideways 39, depending upon the direction of rotation of the shaft. After the brackets 37 and 38 have been 25 adjusted to the proper height the nuts 43 are again tightened to lock them in fixed position.

The housing 50 suspended between the brackets 37 and 38 is in the form of a box-like cradle having an opening in its top with a removable cover 30 51 set thereover. The side walls of the housing 50 are provided with bores for receiving a pair of cylindrical hubs 55 and 56 held therein by bolts 57 passing through flanges 58 on the hubs. A horizontal shaft 60 passes through the bore 35 of the right-hand hub 56, see Fig. 4, with its reduced end 61 journaled in a bearing 47 at the lower end of the bracket 38. The opposite hub 55 has a larger bore to adapt it to receive the reduced end of a sleeve 62 integral with the hub of 40 a pinion gear 139 rotatably mounted on a relatively short shaft 63. The shaft 63 is journaled in the bearing 47 on the left-hand bracket 37 and projects therefrom in axial alignment with the shaft 60. Through this arrangement the two 45 shafts 60 and 63 provide a pivot mounting for the housing 50 to adapt it to be oscillated about a fixed axis for a purpose as later explained. The shaft 63 is connected to oscillate the rocker-shaft 19, previously mentioned as employed for actuating the stop-motion of the machine, being coupled thereto by a universal-joint 65. The last-described arrangement permits vertical displacement of the shaft 63 with the adjustment of the bracket 37 without breaking its connection with 55 the rocker-shaft 19.

Fast on the shaft 60 within the housing 50 is a crank-arm 66 keyed to the shaft at 67 and secured in place axially by a set-screw 68. The lower end of the crank-arm 66 carries a stud 71, 60 on which is journaled a bowl or roller 70 engaging a helical groove 74 in the periphery of a cylindrical cam 75. As shown in Fig. 5, the cam 75 is keyed at 76 to a shaft 77 extending transversely within the housing 50 with its reduced 65 ends journaled in bearings 78 bolted to the sides thereof. The end of the cam 75 is counterbored at 79 to receive a shouldered portion 73 on the shaft 77 which holds the cam from axial displacement in one direction. Axial displacement 70 of the cam 75 in the opposite direction is prevented by the hub of a worm-wheel 80 keyed to the shaft 77 at 81 and held against the end of the cam by a nut 82 screwed onto a threaded portion 75 of the shaft. The cam 75 is extended in a hub 75

at its opposite end and formed with an integral spur-gear 83 which drives a train of gearing to be later described.

Extending at right-angles below the shaft 77 is a horizontal drive-shaft 85 formed with a worm 86 which meshes with the worm-wheel 80, see Fig. 4. The ends of the shaft 85 are journaled in ball-bearings 87 and 88 mounted in the end-walls of the housing 50. As illustrated in Fig. 4, the ball-bearings 87 and 88 are pocketed in journal-boxes 89 secured to the side walls of the housing 50 by means of bolts 90. The inner race of the ball-bearings 87 abuts the side of a flange 91 on the shaft 85 and a double-grooved pulley 92 keyed to the shaft at 93 has its hub reduced and extended into the housing 89 to abut the opposite side of the race. The pulley 92 is arranged in alinement with the pulley 30 on the roll-shaft 11, being held in the shaft 85 by a nut 94 set up against a washer 95. An annular cap 96 secured to the outer end of the journal-box 89 by the bolts 90 serves as a closure therefor. The pulley 92 is connected to drive the pulley 30 on the drive-roll shaft 11 by a pair of endless V-shaped belts 99.

The right-hand end of the drive-shaft 85, as viewed in Fig. 4, is provided with a flange 101 and keyed to the shaft at 102 between the flange and the inner race of the ball-bearing 88 is a spur-gear 103. The inner ball-race is held against the side of the gear 103 by means of a nut 104 screwed onto the threaded end of the shaft 85 and set up against a washer 105. The outer ball-race of the bearing 88 is held against the inner flanged end of the journal-box 89 by an annular cap 106 fastened in place by the bolts 90. With this form of construction the axial thrust of the shaft 85 is taken by the ball-bearing 88.

A second transverse shaft 108, see Figs. 4 and 5, extending parallel to the shaft 85 is journaled in ball-bearings at the sides of the housing 50 with a mounting substantially identical with that above described and therefore not herein shown in detail. Keyed to the shaft 108 at 109 is a spur-gear 110, shown in Fig. 5, which meshes with the spur-gear 103 on the shaft 85. The shaft 108 projects from the side of the housing 50 to carry a pair of double-grooved pulleys 111 and 112 keyed thereto and held in place by a nut 113. The outer pulley 112 is connected to drive the pulley 35 on the drive-roll shaft 13 by a pair of V-shaped belts 100.

Referring to Fig. 2 of the drawings, the pulley 111 is connected by a pair of belts 116 to a similar pulley 114 fast on the armature-shaft of an electric motor 115. The motor 115 is bolted to a bed-plate 117 which may be mounted for vertical adjustment upon a base-plate 118 by means of bolts 119. A suitable manually-operable switch, not herein shown, is usually provided for switching the current to the motor to control the drive for the whole machine.

It has been stated that the present ribbon-breaking device operates to periodically accelerate and retard the speed of rotation of the drive-rolls 10 of the several winding units. This is accomplished by rocking the housing 50 about the axis of the shafts 60-63 to alternately tighten and loosen the belts 99 and 100 whereby they are caused to alternately grip and release their hold upon the pulleys 30 and 35 which rotate the drive-roll shafts 11 and 13.

As the shaft 108 is driven from the motor 115 by the belts 116 the worm 86 rotates the worm-wheel 80 to turn the cam 75 whereby to oscillate

the crank-arm 66 and thereby the shaft 60. Means are provided for limiting the swinging movement of the crank-arm 66 under the action of the cam 75 to regulate the extent of rocking motion imparted to the cradle or housing 50. When the limit of movement of the arm 66 is reached the roller 70 remains stationary whereof it will cause the cam 75 to be moved bodily in the direction of its axis during its further rotation. By this action the housing 50 is swung on its pivot, first in one direction and then in the opposite direction, to tighten and loosen the belts 99 and 100. The means for controlling the range of action of the arm 66 is constructed and arranged as next described.

As shown in Fig. 4, the reduced end 61 of the rocker-shaft 60 projects beyond its right-hand bearing 47 to receive a rectangular block 121, see also Fig. 3, which is secured fast thereto by a set-screw 122. Fitted to slide in a vertical slot 123 in the outer face of the block 121 is an adjusting member or arm 125. The arm 125 is provided with a slotted opening 126, see Fig. 3, through which projects a bolt 127 with its end screwed into a threaded hole in the block 121. The upper end of the arm 125 is provided with a triangularly-shaped opening 128 having its apex at the bottom as shown in Figs. 2 and 3. Referring to Fig. 4, the end of the adjusting shaft 42, previously described, is reduced in diameter to provide a stop-pin or stud 130 which projects through the triangular opening 128 in the arm 125 to limit the swinging movement of the latter in the manner and for the purpose as later explained.

It has been stated that the rocker-shaft 19 for the stop-motion is oscillated from the shaft 63 and the means for imparting motion to this latter shaft comprises connections as next briefly described. Referring to Fig. 5, the gear 83, previously mentioned, meshes with a similar spur-gear 132 on a stub-shaft 133 journaled in a bearing 134 on the side of the housing 50. The gear 132 carries a bevel-gear 135 meshing with a similar bevel 136 free to turn on the shaft 60 and having the end of its hub keyed to the sleeve 62 at 137, see Fig. 4. The sleeve 62 is formed with the gear 139, previously mentioned, which meshes with a spur-gear 140 fast on a stub-shaft 141 journaled in a bearing 142 on the bracket 37 and held in place by a collar 143 at its outer end. The gear 140 carries an eccentric disk 145 on its side, see Fig. 6, with an eccentric-strap encompassing its periphery and formed with a crank-arm 146. A second crank-arm 148 is secured fast to the shaft 63 by a set-screw 149 and carries a pin 150 at its end engaging a hole in the end of the eccentric-arm 146. Through these connections the shaft 63 is rocked to oscillate the rocker-shaft 19 connected thereto by the universal joint or coupling 65; the arrangement being such as to impart a slower rate of movement to the shaft 19.

The parts of the various mechanisms having now been described in detail, the method of operation of the complete machine will next be explained. The belts 99, 100 and 116 are placed over their respective pulleys to connect the ribbon-breaking mechanism with the drive by rocking the cradle 50 first one way and then the other as required. The tension of the belts 99 and 100 is regulated by adjusting the brackets 37 and 38 to raise or lower the cradle 50. This is accomplished by inserting a rod in the hole 49 to turn the adjusting shaft 42 after the nuts 43.

at its ends have been loosened. By turning the shaft 42 in its bearings the eccentric disks 40 may be rotated to either raise or lower the brackets 37 and 38 in the manner as before indicated. The distance between the driving shafts 85 and 108 carried in the housing 50 and the drive-roll shafts 11 and 13 may thus be shortened or lengthened so that the pairs of belts 99 and 100 are placed under proper tension to effect the drive, after which the nuts 43 are tightened to maintain the parts in their adjusted position. The pair of belts 116 are placed around the pulleys 111 and 114 to effect the connection between the driving mechanism and the motor 115.

To complete the adjustment at the driving end of the machine the control-arm 125 may be moved vertically in the slot 123 of the block 121 and secured fast thereto by the bolt 127, whereby to regulate the extent of rocking motion of the housing 50. The arm 125 is herein illustrated, by way of example, as adjusted to its lowermost position with the fixed stud 130 projecting through the widest part of its triangular opening 128. With this adjustment the arm 125 is permitted to swing back and forth with a maximum range of throw during the oscillation of the shaft 60, and consequently the cam 75 will be moved axially to rock the housing 50 to the minimum extent as will be later explained.

Referring to Fig. 1 of the drawings, the machine is prepared for winding by mounting a suitable wooden or fiber cone-tube or yarn-receiver C to rotate on the spindle 15. For this purpose the arm 16 is raised on its pivot and the spindle 15 swung outwardly on its swiveled joint at the outer end of the arm in accordance with the usual method. After the cop-tube C is in place the spindle 15 is swung back into position above the drive-roll 10 and the arm 16 lowered to bring the surface of the tube into driving contact with the periphery of the roll. The strand of yarn y or other material is led up from its source of supply through a tension-device, not herein illustrated, thence drawn across the periphery of the drive-roll 10 and its end attached to the cop-tube C in any suitable manner.

The drive-roll 10 is rotated continuously during the operation of the machine and as the cop-tube C makes contact with its periphery it will be driven from the roll to wind on the yarn. As the yarn is taken up by the rotation of the cop-tube C the strand y enters the helical groove or grooves 8 and 9 on the periphery of the roll 10 to be traversed thereby to deposit it on the receiver in helical coils which make several turns first in one direction and then in the opposite direction. In this way the yarn is given a continuous traverse from one end of the cop-tube 10 to the other and back again to build up a succession of courses forming overlying layers which constitute the yarn body or package.

At the start of the winding the rotative speed of the cop-tube C is approximately the same as that of the drive-roll 10 and the yarn will be laid from end to end of the tube with a number of coils equal to the number of turns in the groove or grooves 8 and 9. As the yarn builds up on the cop-tube C the latter recedes from the drive-roll 10 and with the increase in diameter of the yarn mass its angular velocity or speed of rotation is gradually lessened, due to the increasing disparity between its diameter and that of the drive-roll. In other words, there is a constant change in ratio between the ro-

tative speed of the package and drive-roll and, consequently, there will be a corresponding variation in the number of turns laid on the surface of the package, or in the "wind" as it is called.

At the start of the winding the yarn coils are laid in "open" or spaced relationship, but when the "wind" changes the spacing between the turns is lessened and the coils gradually close up and eventually tend to crowd together in bands or "ribbons". This crowding or piling of the yarn coils takes place each time the wind changes from a greater to a lesser number of even turns and ordinarily causes a "ribbon wind" on the surface of the package. When several coils are laid over each other in the "ribbon" they tend to slip and slide out of place and roll on the surface of the package. This disturbs the twist of the yarn and tends to weaken it so that its quality is impaired and, as another serious defect, the "ribbon" prevents the yarn from delivering freely when it is drawn off over the end of the package. The present invention operates to overcome this defect of "ribbon wind" in "drum-wound" packages by periodically disrupting the synchrony between the rotation of the package and the traverses of the yarn thereon.

The machine is driven by the belts 116 connecting the pulley 114 of the motor 115 with the pulley 111 on the shaft 108. The shaft 108 is rotated in a contra-clockwise direction as viewed in Figs. 2 and 5 while the opposite shaft 85 is rotated in a clockwise direction from the shaft 108 by the gears 110 and 103.

Assuming for the purpose of the following explanation that the housing 50 is in the position shown in Figs. 2 and 5 with the control arm 125 swung toward the right and limited from further movement by the fixed stud 130 engaging the left-hand side of its slot 128, then the pulley 92 will have been drawn downwardly to tighten the belts 99 which connect it with the pulley 30 on the drive-roll shaft 11. At this juncture the opposite shaft 108 will be raised toward the other drive-roll shaft 13 so that the pulley 112 will have been lifted slightly to slacken the belt 100 which drives the pulley 35. At this point in the cycle of operations of the ribbon-breaking mechanism the shaft 11 will be driven at maximum speed while the shaft 13 will have had its speed retarded under the effect of inertia and such friction as occurs in the bearings, due to the release of tension on the belt 100 which allows it to slip on the peripheries of the pulleys 35 and 112. It will be understood that as each of the shafts 11 and 13 carries a plurality of drive-rolls 10 the load is multiplied by the cumulative weight and inertia of the several rolls.

The shafts 85 and 108 are driven continuously at a constant rate of speed from the motor 15 and consequently the shaft 11 carrying the cam 75 will be driven continuously, but at a relatively slow rate of speed by the worm 86 and gear 80 connecting the two shafts. A relatively slow rocking motion is therefore imparted to the crank-arm 66 to oscillate the shaft 60 carrying the control arm 125. During the turning of the cam 75 the crank-arm 66 is rocked first to swing the control arm 125 from one extreme of throw to the other extreme and with the parts in position as shown in Figs. 2 and 5, and last described, the arm 125 will be rocked to the left until the right-hand side of its slot 128 brings up against the fixed stud 130 as shown in Fig. 3 of the drawings. At this juncture the arm 75

125 is held from further movement and since the cam 75 has a throw greater than that required to rock the arm 125 to its extreme of movement in either direction the cam itself will be moved bodily to the left as the roller 70 is held immovable at the end of its throw. The movement of the cam 75 in the direction above indicated acts to swing the whole housing or cradle 50 to the left as viewed in Fig. 3, thereby 5 raising the pulley 92 toward the pulley 30 to slacken the belt 99. The slackening of the belt 99 causes it to slip on the pulleys 30 and 92 to lessen its driving effect so that the drive-roll shaft 11 has its speed reduced by the inertia of 10 the parts and other causes. Meanwhile, as the belts 99 are slackened the pulley 112 is rocked downwardly to tighten the other pair of belts 100 to cause the full effect of the driving force 15 to be transmitted to the pulley 35 to speed up the drive-rolls carried on the opposite shaft 13.

As the cam 75 continues its rotation the opposite return portion of its groove 14 will act on the roller 70 to rock the crank-arm 66 back in the opposite direction to swing the control arm 125 20 toward the right as viewed in Fig. 3. The control arm 125 is moved in this direction until the left-hand side of its triangular slot 128 brings up 25 against the fixed stud 130, whereafter as the roller 70 is held stationary it will force the cam 30 75 bodily toward the right to rock the casing 50 in the same direction. The belts 99 are thus 35 again tightened on the pulleys 92 and 30 and the belts 100 between the pulleys 112 and 35 are concurrently slackened to effect the result first 40 explained; that is, an acceleration in the speed of the shaft 11 and a corresponding deceleration in the speed of the shaft 13.

The ribbon-breaking mechanism continues to 45 operate in the manner explained to effect an alternating slackening and tightening of the belts 99 and 100 with a consequent deceleration and acceleration in the speed of the shafts 11 and 13 which carry the drive-rolls 10 for rotating the packages being wound.

Now it would appear that since the cop-tubes C and the packages wound thereon are rotated by 50 surface contact with the rolls 10 the speed of rotation of the packages should remain the same as that of the rolls. This is not the case, however, since there is necessarily some slippage between the surface of the packages and the peripheries of the drive-rolls due to various conditions. The cop-tubes C and the yarn wound thereon are of considerable mass and the weight 55 thereof increases with the growth in the winding. Moreover, as the packages are driven at a high rate of speed the force of momentum is very considerable. Hence when the speed of the drive-rolls 10 is retarded the velocity of the packages 60 is not materially affected so that they continue their rotation at substantially the maximum rate.

It has been determined in practice that due to 65 slippage between the surface of the package and the drive-roll the retardation in the speed of the roll does not appreciably alter the speed of the package. It is therefore the fact that the intermittent change in the speed of the roll 10 as controlled by the operation of the ribbon-breaking mechanism has only one effect, that is to change 70 the ratio between the traverse of the yarn and the angular velocity of the package being wound. That is to say, the action of the ribbon-breaking mechanism is to intermittently speed up and retard the rate of traverse of the yarn on the pack- 75 age while the angular velocity of the latter re-

mains substantially constant. In this way, the synchronism of the traverse with the rotation of the package is disrupted with the result that the usual crowding or piling of the yarn-turns on the surface of the winding is prevented to eliminate ribbon wind as usually present in drum-wound packages. 5

It has been noted that in the present invention means are provided for adjusting the control arm 125 to regulate the extent of its throw whereby 10 to control the range of movement of the rockable housing or cradle 50 which carries the belt pulleys 92 and 112. Through this means the duration of driving contact of the belts 99 and 100 on their respective pulleys may be regulated to control 15 the variation in speed of the drive-roll shafts in accordance with different requirements. With the arm 125 adjusted to the position shown in Fig. 3 of the drawings a maximum throw of the control arm is obtained before the crank-arm 20 66 is arrested in its motion to effect the shifting of the cam 75 which rocks the housing 50. With this setting of the parts the pulleys 92 and 112 will be moved to only a minimum extent with a dwell between their motions so that the alternate 25 periods of driving contact and release of the belts will be relatively extended.

On the other hand, with the control arm 125 adjusted toward its uppermost position it will have only a slight range of movement as governed by the apex portion of its slot 128 and therefore the crank 66 will remain in fixed position longer to cause the cam 75 to be moved further to rock the housing 50 with the maximum extent of motion. If required, the full throw of 30 the cam 75 may be utilized to swing the housing 50 to the maximum extent so that the belts 99 and 100 will have only a relatively short period 35 of driving contact with the pulleys 30 and 35. It will be understood that the control arm 125 is 40 adjustable to various positions between the two extremes to accurately regulate the change in speed of the shafts 11 and 13 and the drive-rolls 10 carried thereby. In this way a greater or less variation in the rate of traverse of the yarn 45 is effected to regulate the disposition of the turns of winding on the package in a manner to prevent any semblance of ribbon winding.

It will be observed from the foregoing that the present invention provides a particularly 50 simple and efficient means for periodically varying the speed of any certain element of the winding mechanism whereby to effect disruption in the synchrony between the rotation of the package and the traverse of the yarn thereon to prevent ribbon winding. The present improved ribbon-breaker may be embodied in the drive of the machine without materially adding to the parts thereof while making for greater compactness to save space. The principal operating elements 55 of the drive are enclosed in the housing 50 to provide for continuous lubrication and prevent injury to the operator from the gearing and other moving parts.

It is to be understood that the present ribbon-breaking mechanism or speed-changing device 60 may be applied to machines of a type different from that herein illustrated, for example, machines wherein the package is rotated from a drive-roll and the yarn traversed by a reciprocating thread-guide or other means. It is also 65 to be understood that while the present device is shown and described as embodied in a preferred form of construction, various modifications may 70 be made in the structure and arrangement of 75

the mechanism without departing from the spirit or scope of the invention. Therefore, without limiting myself in this respect, I claim:

1. In a machine for winding yarn, a variable speed drive for preventing ribbon winding comprising a driven pulley, a driving pulley movable with respect to the driven pulley, means for continuously rotating the driving pulley, a belt connecting said pulleys, and means for periodically moving the driving pulley with respect to the driven pulley at such frequency as to cause the driven pulley to be continuously driven in the same direction at alternately accelerating and decelerating speeds due to alternate gripping and slipping of the belt. 5
2. In a machine for winding yarn, a variable speed drive for preventing ribbon winding comprising a driven pulley, a driving pulley mounted to oscillate about an axis eccentric to that of the driven pulley, means to continuously rotate the driving pulley, a belt connecting said pulleys, said belt gripping the pulleys in one position of the driving pulley and slipping thereon in an opposite position of the driving pulley, and means for oscillating the driving pulley from one to the other of two positions at such frequency as to cause the driven pulley to be continuously driven in the same direction at alternately accelerating and decelerating speeds. 10
3. In a machine for winding yarn, a variable speed drive for preventing ribbon winding comprising a driven pulley, a driving pulley movable with respect to the driven pulley, power-operated means for continuously rotating the driving pulley, a belt connecting said pulleys, and means directly connected to the power-operated means for continuously moving the driving pulley toward and away from the driven pulley to alternately tighten and slacken the belt on the pulleys to periodically change the speed ratio of the pulleys as the belt alternately grips the pulleys and slips thereon, said speed changing being effected without arresting the rotation of the driven pulley. 15
4. In a machine for winding yarn, a variable speed drive for preventing ribbon winding comprising a driven shaft, a non-expandable pulley on the driven shaft, a driving shaft, a non-expandable pulley on the driving shaft, means for continuously rotating said driving pulley, a belt connecting said pulleys, and means for periodically displacing one of said pulleys with respect to the other pulley at such frequency as to cause the driven pulley to be continuously driven in the same direction at alternately accelerating and decelerating speeds due to alternate gripping and slipping of the belt. 20
5. In a machine for winding yarn, a drive for preventing ribbon winding comprising a non-expandable driven pulley, a rockable cradle, a non-expandable driving pulley carried by said cradle, means for continuously rotating the driving pulley, a belt connecting said pulleys, and continuously operated means connected to oscillate the cradle to alternately tighten and slacken the belt to cause it to slip whereby to vary the speed of the driven pulley without arresting the rotation of said pulley. 25
6. In a machine for winding yarn, a variable speed drive for preventing ribbon winding comprising a driven shaft, a pulley on said shaft, a driving shaft mounted for movement toward and away from the driven shaft, a pulley on said driving shaft, a belt connecting said pulleys, and continuously operated means directly connected to the driving shaft to alternately move said shaft toward and away from the driven shaft to periodically tighten and slacken the belt to cause it to slip whereby to vary the speed of the driven pulley during continuous rotation of said pulley. 30
7. In a winding machine, a driven shaft, a pulley on said driven shaft, a driving shaft mounted for movement toward and away from the driven shaft, a pulley on said driving shaft, means for continuously rotating the driving shaft, a belt connecting said pulleys, and means for periodically moving the driving shaft toward and away from the driven shaft to alternately tighten and slacken the belt to cause it to slip whereby to vary the speed of the driven shaft without arresting the rotation of said shaft. 35
8. In a winding machine, a frame, a driven shaft journaled in the frame, a cradle, means on the frame for mounting the cradle for rocking movement toward and away from the driven shaft, a driving shaft mounted on the cradle, means for continuously rotating said driving shaft, aligned pulleys on the driving shaft and driven shaft, a belt connecting the pulleys, and means acting between the driving shaft and frame for periodically rocking the cradle to alternately tighten and slacken the belt to vary the speed of the driven shaft without arresting the rotation of said shaft. 40
9. In a winding machine, a frame, a driven shaft journaled in the frame, a rocker-shaft mounted in the frame below the driven shaft, a cradle mounted on the rocker-shaft for rocking movement toward and away from the driven shaft, a driving shaft mounted on the cradle, means to continuously rotate the driving shaft, aligned pulleys on the driving shaft and driven shaft, a belt connecting said pulleys, and means on the cradle acting between the driving shaft and rocker-shaft for periodically rocking the cradle to alternately tighten and slacken the belt to vary the speed of the driven shaft during its continuous rotation by the driving shaft. 45
10. In a winding machine, a pair of driven shafts, pulleys on said driven shafts, a driving shaft, means to continuously rotate the driving shaft, pulleys on the driving shaft aligned respectively with the pulleys on the driven shafts, belts connecting the pulleys on the driving and driven shafts, and means for periodically displacing the driving shaft to tighten the belt leading to the pulley on one of the driven shafts while slackening the belt leading to the pulley on the other driven shaft to alternately cause each belt to slip whereby to alternately accelerate and decelerate the rate of speed of the driven shafts without arresting the rotation of said driven shafts. 50
11. In a winding machine, a pair of driven shafts, pulleys on said driven shafts, a cradle mounted for oscillatory movement between the driven shafts, a driving shaft on the cradle, means for continuously rotating the driving shaft, pulleys on the driving shaft aligned respectively with the pulleys on the driven shafts, and means for oscillating the cradle to periodically move the driving shaft toward and away from the driven shafts to tighten one of the belts while slackening the other belt whereby to cause each belt to slip in alternate relation to alternately decelerate and accelerate the rate of speed of the driven shafts without arresting the rotation of said driven shafts. 55
12. In a winding machine, the combination of a nonexpansive driven pulley, a rockable cradle, 60

- a nonexpansible driving pulley journaled on the cradle, a belt connecting the pulleys, and a cam driven by the driving pulley for rocking the cradle to cause periodic slipping of the belt.
5. 13. In a winding machine, the combination of a driven pulley, a rockable cradle, a driving pulley journaled on said cradle, a belt connecting the pulleys, a cam journaled on the cradle, means for driving the cam from the driving pulley, and 10 means engaged by the cam to oscillate the cradle.
14. In a winding machine, the combination of a driven pulley, a rockable cradle, a driving pulley journaled on the cradle, a belt connecting the pulleys, a cam carried on the cradle, means for 15 driving the cam, a crank-arm for oscillating the cradle, and means on the crank-arm engaging the cam.
15. In combination, a driven pulley, a rockably-mounted cradle, a driving pulley journaled 20 on the cradle, a belt connecting said pulleys, a crank-arm for rocking the cradle, a cam on the cradle for oscillating the crank-arm, and means for limiting the motion of the crank-arm to cause it to move the cam to rock the cradle with a pre-25 determined range of movement.
16. In combination, a driven pulley, a rocker-shaft, a cradle rockable about the axis of said shaft, a driving pulley carried on the cradle, a belt connecting the pulleys, a crank-arm fast on 30 the shaft, a cam on the cradle for oscillating the crank-arm, and adjustable means for defining the extent of oscillation of the crank-arm to cause the cam to rock the cradle within predetermined limits to alternately tighten and slack-35 en the belt on the pulleys.
17. In combination, a driven pulley, a rocker-shaft, a cradle rockable about the axis of said shaft, a crank for rocking the shaft, a cam journaled on the cradle and connected to oscillate the crank-arm, a driving shaft journaled on the cradle, means connecting said driving shaft to drive 40 the cam, a pulley on the driving shaft, and a belt connecting said pulley with the driven pulley.
18. In combination, a driven pulley, a rockable cradle, a driving pulley journaled on the cradle, 45 means for continuously rotating the driving pulley, means for adjusting the cradle to vary the distance between the driving pulley and
- driven pulley, a belt connecting said pulleys, and continuously operated means for rocking the cradle to alternately tighten and slacken the belt to cause it to slip whereby to vary the speed of the driven pulley during continuous rotation of 5 said pulley by the driving pulley.
19. In combination, a driven pulley, a rockable cradle, a driving pulley journaled on the cradle, means for continuously rotating the driving pulley, a belt connecting the pulleys, a crank-10 arm rockable independently of the cradle, a cam journaled on the cradle and connected to oscillate the crank-arm, means for driving the cam, and means for limiting the extent of throw of the crank-arm to cause the cam to be moved to rock 15 the cradle to a predetermined extent whereby to alternately tighten and slacken the belt to vary the speed ratio of the driven pulley during continuous rotation of said pulley by the driving pulley. 20
20. In combination, a driven shaft, a pulley on said shaft, a rocker-shaft arranged parallel with the driven-shaft, a cradle supported from the rocker-shaft, a driving shaft journaled on the cradle, means for continuously rotating the driving shaft, a pulley on the driving shaft, a belt connecting the pulleys, a cam carried on the cradle, gearing connecting the driving shaft to drive the cam, a crank-arm fast on the rocker-shaft, means on the crank-arm engaging the 25 cam, and means for controlling the range of movement of the crank-arm to cause the cam to be moved bodily to rock the cradle to alternately tighten and slacken the belt to vary the speed of the driven shaft during its continuous rotation 30 35 from the driving shaft.
21. In combination, a driven pulley, a rocker-shaft, a cradle pivoted on the rocker-shaft, a driving pulley journaled on the cradle, a belt connecting the pulleys, a crank-arm fast on the 40 rocker-shaft, a cam on the cradle for rocking the crank-arm, a control-arm connected to oscillate with the crank, and means to limit the rocking motion of the control-arm to regulate the range of motion of the crank-arm whereby to cause 45 it to move the cam to oscillate the cradle.

ERNEST R. SWANSON.
